BUMPER POST, TRACK STIFFENING STRUCTURE THEREFOR, AND METHOD OF STIFFENING EXISTING TRACK

Stanley W. Hayes, Richmond, Ind., assignor to Hayes Track Appliance Company, Richmond, Ind., a corporation of Indiana

Application December 20, 1932, Serial No. 648,070

11 Claims. (Cl. 104—254)

This invention relates to bumper posts, to track stiffening structure therefor and to the method of stiffening existing track at bumper locations before or after the installation of the bumper.

- 5 The track stiffening structure acts in a vertical sense to hold down the track and it may also be, and usually is, so related to the track rails or bumper structure or both as to take sidewise (rail spreading) thrust resulting from car impact 10 and in some embodiments part also of the downward component. The track stiffening structure may be combined with various kinds of existent bumpers of the type in which the bumper head is supported between the rails and delivers stress 15 of impact to the road bed by diverging compression members and by tension members, such for example as the bumper of the patent of this applicant No. 1,705,479, dated March 19, 1929, or that of his application Serial No. 558,283, filed 20 20 August 20, 1931, or that of his application Serial No. 648,069, filed December 20, 1932. The structure referred to may be applied to a bumper already in track being connected thereto indirectly through the rails, or it may be directly, or directly 25 and integrally, united to the bumper post structure.

The building up of the stiffening grid structure, by the method hereinafter set forth, in an existing track and, even where the bumper post has 30 long been a track fixture, evidently has decided utility. The grid itself coacts with the existent track and with the bumper post in combinations recited in the claims.

35 The invention also includes improvements in the compression and in the tension structure useful in themselves even in the absence of the track stiffening structure and applicable wherever they can be of use. The invention will be 40 understood from the following specification and the accompanying drawings. It consists in the subject matter set forth in the appended claims.

45 Referring to the drawings: Fig. 1 is a plan showing the bumper of the aforesaid patent installed in track with the track-stiffening structure associated therewith in accordance with the invention.

50 Fig. 2 is a side elevation corresponding to Fig. 1, the further extension to a considerable distance in advance of the post being indicated in both figures by the breaking away of the various rails.

55 Fig. 3 is a rear end elevation corresponding to Figs. 1 and 2.

Fig. 4 is a plan illustrating a modified embodiment.

ment of the invention in which the post is of the general nature of that set forth and claimed in the pending application, Serial No. 558,283, above referred to, and of the improvement thereon shown and claimed in the application Serial No. 648,069, also referred to above.

Fig. 5 is a side elevation corresponding to Fig. 4, the near rail being removed. The breaking away of the various rails in both Figs. 4 and 5 indicates the considerable further extension of 10 the track stiffening structure and the portion of the track to which it is applied.

Fig. 6 is a transverse vertical section on line VI—VI of Fig. 4 showing in rear end elevation the lower ends of the compression members, the base 15 structure, transverse connecting beam and intermediate rails, and

Fig. 7 is a detail front elevation of the lefthand tension base structure.

Referring to the embodiment of the invention 20 illustrated in Figs. 1 to 3, the post therein shown, that of the patent above identified, has bumper head 1 supported from the road bed by compression channels 2 secured to compression base members 3 bolted respectively to the adjacent 25 rails, and by tension bars 4 hooked over the bumper head and underneath the tension base members 5 and further serving to transmit stress of car impact to the road bed which term is used broadly to indicate the rails, ties, ballast, 30 stiffening structure or any one or more of them. Anchor bars 6 secured to the compression and tension base members are spiked to ties in advance thereof. In order to control the tendency of the 35 track to rise at the point of tension connection to the road bed, and to divide the outward sidewise rail spreading thrust on the compression base members, compression track stiffening structure is built into the existing track at the bumper post location. This structure consists of longitudinal and transverse members built up by the method herein described into a track stiffening grid having one or more transverse members as the case may be. These members are introduced individually into the existing track and are 40 readily connected, preferably by threading one through the other. The illustrated track-stiffening structure when completed comprises a pair of intermediate rails 7 located adjacent the respective track rails, say a foot or so inside them, 45 and extending lengthwise of the track from a point well in advance of the bumper post to its rear a distance substantially twice the length in track of the bumper post and preferably fourteen feet or more. These rails are securely anchored 50

55

to the road bed by spiking to the several ties or otherwise. In both illustrated structures, they are connected crosswise of the track by one or more cross beams 8 which are preferably I-beams 5 and are provided on their upper side, with rail-base-receiving sockets or apertures suitably formed as shown by the pairs of lugs or clips 9 which are best made integral with the beam by welding. The intermediate cantilever anchoring 10 and stiffening beams constituted by these rails are, for full effectiveness, directly or indirectly connected to the track rails or/and to the respective compression base members indirectly, directly, or both directly and integrally. The beam 15 or beams 8 are located in the plane of the ties and are most effective when one of them is placed opposite the compression base members 3 in a plane crosswise of the track and intersecting said base members so as to take the outward sidewise thrust delivered thereto from the bumper head on car impact. In the form of the structure illustrated in Figs. 1-3, the connection of the track stiffening compression receiving structure to the compression base members 20 is indirect through the track rails and not, as it might also be, direct through the compression base or track fixture members 3. The cross beam 8, in the figures referred to has, in addition to the sockets for the intermediate rails already 25 mentioned, track rail base sockets or outside recesses illustrated as each consisting of an end member 10 welded to the cross beam adjacent its end and an inwardly projecting lug 11 welded to the member 10, the cross beam being thus supported and held in place when intermediate rails 30 7 are not present, and being enabled to prevent spreading under outward thrust delivered to the base member under car impact. It will be understood that the parts will be constructed of such 35 size and weight as to insure the requisite strength. While welding is preferred, it is not the only acceptable mode of manufacture. The tie bar cross-connecting the compression base members 3 usually present in the post of the said patent 40 is omitted as unnecessary, and to leave room for the intermediate rails. With this slight omission the track stiffening and stress dividing and dispersing structure can be built up in existing track and applied to bumpers of this sort already installed, and for that matter to practically all 45 bumpers of this general type. The removal of tie-bars or other such minor parts is a preliminary easily effected. The stiffening grid thus has an enlarged field of utility.

50 There are, however, compensating advantages in new bumper posts in connecting the cross beam 8 of the track stiffening structure with the compression base structure of the post, as is shown in the post illustrated in the remaining 55 figures, namely, Figs. 4-7, in which, as will shortly appear the said members are integrally connected.

60 The bumper post of these figures contains features illustrated and claimed in each of the applications above identified. In these figures, bumper plate 12 is supported from the road bed by integral compression structure consisting of divergent compression members 13, which are preferably H-beams located flange side up in the same plane transverse of the track, having their 65 front ends abutting on and welded to the back of the bumper plate, the head structure being braced by plate pieces 14 welded thereto and by side plates 15 as in the head of the post of the application Serial No. 648,069. The respective compression members, as in the said application 70

Serial No. 648,069, abut on and are welded to the abutment member leg 16 of the angle whose other leg 17 extends downward, outward and rearward to the angular compression base plate or track fixture member having a base portion 5 18 and the upstanding rail connecting flange 19, to both of which the leg 17 cornering on the base part 18 is welded. Angular brace plates 20 are located in the plane of the web of the adjacent H-beam, namely, the longitudinal axial plane 10 of the H-beam, fit the angle between the legs 16-17 and are welded therein as well as to the base portion 18 of the compression base plate, whose rail attachment flange 19 is provided with bolt holes and adjacent pads 21. The 15 base portions 18 of the compression base plates have on their underside the usual pads 22 welded thereto. They also have spacer blocks 23 welded to their underside and to the top of the cross beam 24 which thus integrally connects the 20 compression base plates. This beam differing in this respect from cross beam 8 of the track stiffening grid of Figs. 1 to 3 which extends under both track rail bases, stops short of the respective rails. It corresponds, however, to cross beam 8 thus having a double function. In the bumper of Figs. 4 to 7, the stiffening structure is 25 provided with an additional cross beam 34 some distance in advance of the tension structure.

The compression structure thus described is 30 bolted in track in the usual way. The means of tension connection from the bumper head to the road bed are improvements over the tension structure illustrated in the application Serial No. 648,069, above identified, and preferably consist 35 in a unitary structure having a cross bar 26 to which are welded the divergent tension bars 27 passing through holes near its respective ends and extending downward, outward and forward through tension base members or track fixtures 40 28 to which they are welded, and which have upright flanges 29 provided with bolt holes and tension pads 30 and adapted to be bolted to the rail web in the usual way. These tension members are provided with space blocks 31 welded 45 thereto and to the top of the tension cross beam 32 adapted to seat under both of the rails, the bases of which are received in the recesses thus formed.

The tension structure is further strengthened 50 by the provision of a pair of brace plates or clips 33, located in a plane normal to the face of the I-beam that is, lengthwise of the track one in front and the other behind the I-beam to receive the head and web between 55 them and strongly brace the structure, the members 33 being welded to the underside of the base 28 to the space block 23 and to the top flanges and web of the I-beam. It will be understood that this integral tension unit may be used in a bumper post whose compression structure is not a unit and which may or may not be provided with track stiffening and stress resisting structure. It will appear further that the tension base structure just described may be used where 60 the tension bars are not integral with the tension cross bar or other structure associated with the bumper head.

As in the track stiffening structure already described, intermediate rails 7 adjacent the respective tracks, having substantially the same location and length as the intermediate rails 7 referred to earlier in the specification and anchored to the road bed as by spiking to the several ties are introduced into the existing track by 75

threading (shoving) through sockets carried by one or more cross beams 24, 34, these sockets being formed preferably as in the construction already described by lugs or clips 9 welded in 5 pairs to the top of the cross beam in due spaced relation to receive the adjacent rail base. The cross beam 34, like the cross beam 8, seats under both rails. It is located preferably near the front ends of the intermediate rails. Cross beam 10 24, which as already stated, integrally connects the respective compression base members forms with the rest of the compression structure in the illustrated structure an integral unit, this being greatly preferred to an arrangement lacking integrality and weaker as well as less convenient for 15 purposes of shipment and installation. It will be apparent that the intermediate rails divide the sidewise stress due to compression, so that it is not all taken by the adjacent rail, and distribute it to the various ties to which the intermediate rails are spiked. The outward component of the thrust carried by each compression member operates in the axial plane of the beam 20 24 which thus resists it effectively.

25 The compression unit may be bolted in track and the tension unit bolted thereto and bolted in track, and the intermediate rails afterwards shoved endwise through the aligned sockets on the cross beams and are then spiked in place. In 30 doing this, one of the track rails is first moved out and later replaced.

I claim:

35 1. A track stiffening grid structure for association with an existing track at a bumper post location, comprising separate members some of which are longitudinal and one of which is transverse with respect to the track and in a plane intersecting compression base members of the post, introduced into the existing track and connected 40 together therein as a stiffening structure, means for connecting said longitudinal and transverse members, means anchoring the longitudinal members to the road bed, and means for connecting the said transverse member to the respective track 45 rails in said plane.

50 2. Track stiffening and spread preventing structure for bumper post locations in existing track, comprising one or more cross beams extending crosswise of the track and having beam receiving sockets adjacent and spaced from the respective track rails, beams intermediate the track rails and threaded through said sockets, said beams extending lengthwise of the track from a point well in advance of the bumper post 55 to its rear, and means associated with the cross beam or beams for connecting said structure to the respective track rails to prevent them from spreading under car impact.

60 3. A bumper post comprising a bumper head, compression members diverging downward, outward, and rearward therefrom, compression base structure to which thrust of car impact is transmitted by the compression members and which 65 includes a track fixture adjacent each of the respective rails at points opposite each other in the track, each said track fixture having an upstanding rail attachment flange and a base flange both receiving said thrust, a cross beam connecting 70 both track fixtures across the track and stopping short of the adjacent rail base, said cross beam being provided with rail base sockets adjacent the respective track fixtures, track stiffening rails threaded through said rail base sockets and anchored to the road bed and extending from a point 75

well in advance of the bumper post to its rear, and tension means for connecting the bumper head to the road bed at points in advance thereof at the adjacent track rails and opposite each other in the track. 5

4. A bumper post comprising a bumper head, compression members diverging downward, outward, and rearward therefrom, base structure supporting said compression members and including a base plate member adjacent each of the 10 respective rails, and a cross beam integral with said base plate members and provided opposite and adjacent each of the said base plate members with a rail base receiving socket, intermediate rails between the track rails having their bases located in said sockets, said intermediate rails extending lengthwise of the track from a point well in advance of the post to its rear and being anchored to the road bed, and tension means for distributing 15 stress of impact to the road bed. 20

5. A bumper post comprising a bumper head, means for transmitting stress of impact therefrom to the road bed including compression members diverging downward, outward, and rearward from the bumper head to the road bed at opposite points 25 adjacent the respective track rails, transversely aligned base structures for said compression members at said points, track stiffening and thrust receiving intermediate rails inside and in the plane 30 of the respective track rails and extending from well in advance of the post to its rear, and a plurality of cross beams one in advance of the post and one aligned transversely with the compression base structures and directly or indirectly 35 connected to the respective track rails and to the respective compression base structures, each said cross beam having a rail base receiving socket for each of the respective intermediate rails. 40

6. A bumper post comprising a bumper head, means for transmitting stress of impact therefrom to the road bed including compression members diverging downward, outward, and rearward from the bumper head to the road bed at opposite points adjacent the respective rails, track 45 stiffening and thrust receiving intermediate rails located inside and adjacent the respective track rails, seating on and secured to a multiplicity of ties, and extending from well in advance of the post to its rear, and a cross beam located in line with the points of delivery of compression stress to the road bed by the respective compression members and provided with rail base receiving sockets or apertures for receiving the respective intermediate rails adapted to be shoved there-through, the cross beam being connected to the respective rails at points in line with the compression base structure. 50 55

7. A bumper post comprising a bumper head, means for transmitting stress of impact therefrom to the road bed including compression members diverging downward, outward, and rearward from the bumper head to the road bed at opposite points adjacent the respective rails, track stiffening and thrust receiving intermediate rails anchored to the road bed, located inside and adjacent the respective rails, and extending from well in advance of the post to its rear, and a cross beam located in line with the points of delivery of compression stress to the road bed by the respective compression members and provided with rail base receiving sockets or apertures through which the respective intermediate rails are adapted to be shoved, the cross beam being connected directly or indirectly to the compression base 70 75 structure. 75

8. A bumper post comprising a bumper head, compression members diverging downward, outward, and rearward therefrom to the road bed at the respective track rails, tension means for 5 delivering stress of impact to the road bed, an anchored intermediate rail inwardly adjacent each track rail and extending lengthwise of the track from a point well in advance of the post to its rear, and means for connecting each intermediate rail to the adjacent track rail.

9. A bumper post comprising a bumper head, compression members diverging downward, outward, and rearward therefrom to the road bed at the respective track rails, tension means for 15 delivering stress of impact to the road bed, an anchored intermediate rail inwardly adjacent each track rail and extending lengthwise of the track from a point well in advance of the post to its rear, rail base receiving sockets each adapted 20 to receive one of said intermediate rails, and means for connecting each of said sockets with the adjacent track rail.

10. A bumper post comprising a bumper head, compression members diverging downward, outward, and rearward to the road bed and having 25 compression track fixture base members secured

to the respective track rails at points opposite each other in the track, an anchored intermediate rail inwardly adjacent each track rail and extending lengthwise of the track from a point well in advance of the post to its rear, and means provided with sockets or apertures through which the base of each intermediate rail is shoved or threaded and which has rigid extension to the adjacent track rail and is connected thereto at points aligned crosswise of the track and opposite the 5 respective compression base members.

11. A bumper post comprising a bumper head, compression members diverging downward, outward, and rearward to the road bed and having compression track fixture base members secured 15 to the respective track rails at points opposite each other in the track, an anchored intermediate rail inwardly adjacent each track rail and extending lengthwise of the track from a point well in advance of the post to its rear, and means for 20 connecting each intermediate rail to the adjacent track rail at points aligned crosswise of the track and opposite the respective compression base members.

STANLEY W. HAYES. 25
